UNITED STATES PATENT OFFICE.

GARRETT W. WOODWARD, OF CHICAGO, ILLINOIS, ASSIGNOR TO WOODWARD AUTOMATIC CONTROL CORPORATION, OF CHICAGO, ILLINOIS, A CORPORATION OF ILLINOIS.

BUTTON BLOCK.

1,419,597.

Specification of Letters Patent. Patented June 13, 1922.

Application filed November 29, 1920. Serial No. 427,140.

To all whom it may concern:

Be it known that I, GARRETT W. WOODWARD, a citizen of the United States, residing at 5056 Washington Blvd., Chicago, in the 5 county of Cook and State of Illinois, have invented a new and useful Improvement in Button Blocks, of which the following is a specification.

This invention relates to button blocks 10 and the like and is fully described in the following specification and shown in the accompanying drawings in which:

Figure 1 is a plan view of the button block as applied to the steering column of an 15 automobile;

Fig. 2 is an enlarged plan view of the interior mechanism with the cover removed;

Fig. 3 is an enlarged vertical section on the line 3—3 of Fig. 1;

Fig. 4 is a partial section on the line 4—4 of Fig. 1 and Fig. 5;

Fig. 5 is a partial section on the line 5—5 of Fig. 4; and

Figs. 6, 7 and 8 are partial sections on the 25 lines 6—6, 7—7 and 8—8 of Fig. 2.

In the embodiment illustrated, the button block consists of a housing having top and bottom sections 10 and 11 respectively, which are secured together by means of bolts 12. 30 The lower section is clamped to the stationary tube 13 forming part of the steering column and is supported thereby, above the steering wheel.

The button block is adapted to be used 35 with my automatic gear shifting mechanism disclosed in my application Serial No. 352,648. In this case, however, the wires 15 act as tension members whereas the wires 91^a, etc., of my previous application are 40 under compression. The wires 49, 60, 84, 85, 86 and 87 are tension members and the wires 15 can be connected directly to these to obtain the same previous disclosure. The wires 15 pass down through the tube 16 45 which is rotatably mounted in the tube 17 which in turn is rotatably mounted in the tube 13. The spark advance lever 18 and the hand throttle control lever 19 are mounted on the tubes 16 and 17 respectively, 50 and control the spark advance and throttle in a well known manner.

Each of the wires 15 as previously stated, is connected to mechanism which shifts the transmission gears to reverse, neutral, first 55 speed, intermediate speed or high speed, and

one of these wires is connected to mechanism for applying and releasing the brake. These wires are secured at their upper end by means of screws 15^a to a series of levers 20, 21, 22, 23, 24 and 25 respectively which are 60 pivotally mounted on pins 21 and are drawn downwardly by a series of springs in the gear shifting mechanism (not shown). Plungers 26 are slidably mounted in the upper section of the housing and have longitudinal guide-ways therein in which slide pins 27 by which the plungers are prevented from turning. Buttons 28 are secured to the upper end of these plungers and each is marked as shown in Figure 1 to designate 70 the particular setting of the gears which it controls; R is for reverse, N for neutral, 1 for first speed, etc.

A plate 29 is supported above the levers 20, 21, etc., on posts 30 and has a series of 75 fan-like stops 31 which are hingedly but frictionally mounted thereon by means of screws 32, so as to be movable when some pressure is applied to them. At the side of the housing, these stops engage abutment 11^a 80 and are so formed that they will permit but one of the lugs 33 to pass these stops at any time. One of the lugs 33 is placed on each of the levers 20 to 24 inclusive so that no two of the levers controlling the gear-shifting 85 mechanism can be operated at the same time. It will be observed, however, that no lug is placed on the lever 25 which controls the brake-operating mechanism as it is desired 90 to be able to apply the brake at any time regardless of the position of the gear shifting mechanism.

The letters and numerals on the buttons 28 are made with radium so as to be visible 95 in the dark and openings 34 are formed in the upper housing section 10 immediately in front of the controlling neutral and first, second and third speeds. Above the arcuate plate 29 is secured an arcuate shift 35 having a series of radium spots 36 therein which 100 lie immediately beneath the openings 34. As shown in Figure 2 all of these radium spots 36 are covered except the one in front of the button which had been last actuated. Thus the position of the transmission gears is 105 shown at night by means of the radium spot and in the day time the same spot while not luminous is readily visible for the reason that only one will be shown to be uncovered by the members 31. No radium spot 36 is 110

placed in front of the reverse button marked R for the reason that they are seldom used and then only for a short time. That the gears are in reverse is indicated by the absence of the radium spot in any of the openings 34.

In order to prevent accidental actuation of the reverse button, I have provided its plunger 29^a with a releasing pin 37 as shown in Figs. 1, 4 and 5 which must be pressed inwardly before the button 28 can be depressed. The pin 37 is slidable in a hole in the upper housing section 10 which is at right angles to the hole in which the plunger 29^a is slidable, the peripheries of these two holes slightly overlapping as shown in Figs. 4 and 5. The plunger 29^a has a notch 29^b which is a continuation of the periphery of the hole in which the pin 37 is slidable when the plunger 29^a is at the top of its throw. The pin 37 also has a notch 37^a which is coincident with the periphery of the hole in which the plunger 29^a is slidable. The hole 37^a, however, is normally held out of coincidence with the periphery of the hole in which the pin 29^a is located, by means of a spring 38. Thus it will be seen that the reverse button cannot be depressed until the releasing pin 37 is pushed in until the opening 37^a therein comes into registration with the plunger 29^a. The pin 37 is prevented from turning by the pin 39 which is guided in the slot 40.

A flat arcuate strip 41 lies upon the arcuate ledge 11^a forming part of the lower housing section 11, as shown in Figure 3 and is held thereon by means of a series of guides 42. The strip 41 is broadened as shown in Figure 2 into a plate 41^a to which is secured a yoke 43 as shown in Figure 8 in which is slidably mounted the eccentric 44 which is secured to the revolving tumbler 45 of a well known type of lock which is mounted in the housing. The arcuate strip 41 has secured thereto a series of blocks 46 which lie at one side of the path of the levers 20, 21, etc., as shown in Figures 2 and 6 when the strip 41 is moved to the unlocked position. This is done by means of the key 47 which turns the tumbler 45.

With the engine running the brake remains applied only so long as the lever 25 is depressed. In order, therefore, to lock the lever 25 so that it cannot be moved either to set or release the brake, a pin 25^a as shown in Figure 7 is secured to the outer end thereof and a block 46^a is secured to the plate 41^a, so that as the plate 41^a is moved by means

of the key 47 it will withdraw the block 46^a and permit movement of the lever 25, setting and releasing the brake. As the plate 41^a, however, is moved back to its locking position as shown in dotted lines, the block 46^a is moved into the path of the pin 25^a so that it cannot be depressed from the full line position shown in Figure 7. If the plate 41^a is moved while the lever 25 is in the depressed position as shown in dotted lines, the plate 41^a will pass over the pin 25^a thereby preventing the brake from being released.

The arcuate strip 41 is also provided with hooks 41^b which are adapted to engage the lugs 10^b secured to the upper housing section 10 as shown in Figure 6, thereby securely locking the upper and lower housing sections 75 together when the key 47 is removed.

While I have shown and described but a single embodiment of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new and desire to secure by Letters Patent is:

1. A button block comprising a series of buttons, a series of levers, each movable by a button, an element movable by each lever, means for preventing more than one of said levers being moved from its normal position at a time, and means uncovered by said last mentioned means for indicating which button was last depressed.

2. A button block comprising a series of buttons, each of which is operatively connected to a member to be moved, a housing for said members consisting of top and bottom sections and a lock for locking said sections together and for locking all of said members against movement.

3. A button block comprising a series of buttons, a series of levers, each movable by a button, an element movable by each lever, a series of spaced members for preventing more than one of said levers being moved from its normal position at a time, and means opposite each button and visible in the dark and normally covered by said spaced members, said means being uncovered by the last operated button for indicating which button was last depressed.

GARRETT W. WOODWARD.
